H. RESCH

TYPEWRITING MACHINE

Filed Feb. 21, 1921

Inventor:

Henry Beech
by D. C. Buckley
Attorney

UNITED STATES PATENT OFFICE.

HENRY RESCH, OF BAYONNE, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed February 21, 1921. Serial No. 446,599.

This invention relates to typewriting machines, and more particularly to an auxiliary paper-roll supply to be used in connection with listing work on bookkeeping machines 5 equipped with tally-strip mechanism.

In certain kinds of work, wide tally-strips are used in bookkeeping machines in connection with ledger posting and similar work. It has been found, however, that this class 10 of work is not sufficient in many cases to keep the machines in continuous use during working hours. Consequently, it has been proposed to do listing work, such as the listing of checks, on the bookkeeping machines 15 when not otherwise in use.

In carrying out the present invention, provision may be made of an auxiliary paper-roll supply at the rear of the platen-frame.

When the work, in which a wide tally-strip is used, is completed, the operative 20 may rewind the tally-strip on the delivery roll at the rear or may remove the tally-strip from the platen in any other manner.

The strip from the auxiliary paper-roll may 25 then be passed around the platen and attached to the winding mandrel of the regular tally-strip mechanism, so that the strip may be wound thereon by the line-spacing mechanism as the listing of the numbers or 30 amounts proceeds.

Preferably, the auxiliary paper-roll is carried by a bracket mounted near the left-hand end of the rear paper-table, to which it is secured by screws passing through holes 35 in the bracket and the paper-table and threaded into a plate or strap in back of the paper-table. Preferably, also, the side plates of the supporting bracket are so inclined to the surface of the rear paper-table as to 40 prevent the edge of a work-sheet from being interfered with when the platen is reversely rotated.

Other features and advantages will hereinafter appear.

45 In the accompanying drawings,

Figure 1 is a front elevation of a platen-frame of an Underwood typewriting machine with my invention applied thereto.

Figure 2 is a side view of substantially the same parts as shown in Figure 1. 50

Figure 3 is a perspective view of an auxiliary paper-supply device mounted on the rear paper-table.

In the Underwood typewriting machine, type-bars 11 strike upwardly and rearwardly 55 against the platen 12, which is journaled by means of an axle 13 in the ends 14 and 15 of the platen-frame which also comprises a plate 16, forming a paper-table upon which work-sheets are supported as they are introduced in the machine and fed forwardly 60 between the platen and the usual feed-rolls 17 and 18.

In order to rotate the platen, provision 65 may be made of line-space mechanism which includes a ratchet-wheel 19, secured to the axle 13 at its left end, and a pawl 20 having a tooth 21 adapted to engage the teeth of the ratchet-wheel. The pawl 20 may be pivoted at 22 on a line-space slide 23 which may be 70 actuated by a line-space lever 24.

Provision may also be made of tally-strip mechanism, so that a tally-strip may be used 75 to receive carbon copies of work typed on work-sheets, a condensed list of the totals of all the pieces of work usually being printed on the tally-strip. Mounted on the ends 14 and 15 of the platen-frame are brackets 25 and 26 which form supports for shafts 27 and 28 extending parallel to the 80 axis of the platen, the delivery shaft 28 being detachably mounted on the brackets 25 and 26 in a manner more fully described in the patent to Frederick A. Hart, No. 1,281,160, granted October 8, 1918. The 85 shaft 27 extends through side plates 29 and 30, respectively, of the tally-strip supporting frame, and the plates 29 and 30 are held in position by means of the shaft 28 extending through open-ended slots 31 therein. 90

The tally-strip roll is mounted on the delivery shaft 28, and the tally-strip, when in use, extends around the platen 12 to a mandrel or drawing roll 32 journaled in said side plates 29 and 30. Actuation of the 95 mandrel 32 may be effected by means of

a link 33 connecting the line-space slide 23 with an arm 34 mounted on said shaft 27 and having thereon a pawl 35 to engage a ratchet-wheel 36 fixed on said shaft 27. 5 Splined on said shaft 27 is a gear 37 which is normally held in mesh with a gear 38 or the mandrel 32 by means of a spring 39. Gear 37 may, however, be shifted out of mesh with gear 38 against the tension of 10 spring 39 by means of a shift-rod 40, the head 41 of which is engaged by a cam 45 on a handle 46, pivoted on said shaft 27.

The mechanism so far described may be substantially the same as that disclosed in 15 said patent to Hart.

In order that listing of items, such as, for example, the amounts of checks, may be effected when the machine is not otherwise in use, provision may be made of a support 20 47 for a narrow-strip supply, mounted on the paper-table 16. The support 47 may consist of a base plate 48 to rest on the upper surface of the paper-table 16, two side plates 49 and 50; and a plate 51 connecting the side 25 plates 49 and 50, and extending upwardly from the base plate 48. Preferably, the support 47 is connected with the paper-table 16 by means of screws 52 extending through openings in the base plate 48 and corresponding openings in the paper-table 16; the screws being threaded on the lower side of the paper-table 16 into a plate or strap 53. In order to avoid interference by the support 47 with work-sheets in the machine 30 when the narrow-strip is not in use, the support may be positioned near one end of the platen-frame and the forward edges of plates 49 and 50 may be inclined to the paper-table, so that, when the platen is reversely 35 rotated, the rear edge of a work-sheet in use will be lifted so as to pass over support 47.

The narrow strip or listing strip 54 may be in the form of a roll which is mounted 40 in the support 47 by means of a core or mandrel 55 extending therethrough and detachably supported in plates 49 and 50. As shown in Figures 2 and 3, the core 55 is flattened near its ends, so that the flattened 45 portion may be passed through slots 56 in the ends of plates 49 and 50 into a circular opening 57 in each of the plates, and then turned to maintain it in the brackets. Accidental turning of the core 55 may be prevented 50 by means of a spring 59 engaging one of the flattened sides of the core adjacent the plate on which the spring is mounted. A leaf spring 60 may be mounted 55 on the support 47 so as to engage the listing strip roll and act as a brake therefor.

When it is desired to use the listing strip, the tally-strip is withdrawn from the platen, being preferably wound on the roll carried by the shaft 28, and the listing strip is led 60 forward from the roll over the upper edge

of the plate 51 beneath the platen and up to the mandrel 32, to which it is connected by passing the end thereof through a slot 61 in said mandrel. It is very desirable, after the tally-strip has been withdrawn 70 from the platen and wound about the roll carried by the shaft 28, that the tally-strip roll shall not be caused to rotate during typing on the listing-strip 54 either by engagement of the listing-strip 54 with the periphery of the tally-strip roll or otherwise. With the construction hereinbefore described, it will be noted that the tally-strip, after it has been wound upon the shaft 28, 75 will be out of the way of the listing strip 54, whether the tally-strip roll or listing strip roll is full or nearly depleted. Accordingly, the tally-strip roll will not be rotated by the listing strip 54 under any conditions of use of the mechanism, and will not interfere with or obstruct the passage of the listing strip about the platen, nor will the tally-strip be unwound from the tally-strip roll. By actuation of the line-space lever 24, the mandrel 32 may be given a 80 line-space movement and the listing strip advanced step by step.

Preferably the support for the listing strip roll is attached to the rear paper-table of a bookkeeping machine and the numbers 85 listed are also added:

It will be evident that by means of the present invention the range of work to be done on such machines is increased, and that the loss which would otherwise occur, due to allowing the machines to stand idle, 90 will be greatly decreased.

Variations may be resorted to within the scope of the invention, and portions of the improvements may be used without others. 105

Having thus described my invention, I claim:

1. A typewriting machine comprising a platen, a platen-frame including a rear paper-table, and a bracket for a narrow strip roll mounted on said paper-table, said bracket comprising side plates, the foremost edges of which are inclined toward the paper-table, so as to prevent interference with the rear edge of a work-sheet when the platen is reversely rotated. 110

2. A typewriting machine comprising a platen, a platen-frame including a rear paper-table, a bracket for a narrow strip roll mounted on said paper-table, said bracket comprising side plates, the forward edges of which are inclined toward the paper-table, so as to prevent interference with the rear edge of a work-sheet when the platen is reversely rotated, and a leaf 120 spring to press against the side of a roll supported in said bracket.

3. A typewriting machine comprising a platen, a platen-frame including a rear paper-table, a bracket for a narrow strip 125

roll mounted on said paper-table, said bracket comprising side plates, the forward edges of which are inclined toward the paper-table, so as to prevent interference with the rear edge of a work-sheet when the platen is reversely rotated, and braking means to resist the unrolling of a roll mounted in said bracket.

4. A typewriting machine comprising a platen, a platen-frame provided with a rear paper-table, wide tally-strip mechanism including a delivery spool, a receiving spool or mandrel, and a line-spacing mechanism therefor, a spool mounted on the paper-table, in alignment with the receiving spool longitudinally of the machine, for delivering a much narrower strip to the receiving spool,

and means mounted on the ends of the platen-frame for supporting the wide tally-strip mechanism, said supporting means for the wide tally-strip delivery spool being positioned to enable the wide tally-strip to be withdrawn from the platen and wound about its delivery spool out of the way of the narrower strip in its passage around the platen to the receiving spool.

5. A typewriting machine comprising a platen, a platen frame, a rear paper table, and a support for a supply roll mounted upon the paper table and comprising side members having inclined portions to deflect a work sheet upwardly over the supply roll when the platen is reversely rotated.

HENRY RESCH.
